UNITED STATES PATENT OFFICE.

THOMAS S. LEVIS, OF CHICAGO, ILLINOIS, ASSIGNOR TO MODEL FORM COMPANY, OF CHICAGO, ILLINOIS, A CORPORATION OF ILLINOIS.

ADJUSTABLE FRICTIONAL CLAMPING DEVICE.

1,147,029.

Specification of Letters Patent. Patented July 20, 1915.

Application filed July 26, 1913. Serial No. 781,406.

To all whom it may concern:

Be it known that I, THOMAS S. LEVIS, a citizen of the United States, residing in Chicago, county of Cook, and State of Illinois, have invented certain new and useful Improvements in Adjustable Frictional Clamping Devices, of which the following is a specification.

My invention relates to frictional clamping devices, having to do particularly with adjustable clamping devices, my invention being more particularly useful in connection with model dress forms for yieldingly holding them in adjusted positions, an object of my invention being to provide a device of the character described which is simple of construction, cheap to manufacture and positive in its holding operation.

In the accompanying drawing I have illustrated embodiments of my invention in which,

Figure 1 illustrates a skirt frame for dress forms embodying my invention; Fig. 2 is a side elevation of Fig. 1 but showing only part 25 of the skirt form; Fig. 3 is a top view of Fig. 1 being broken away at several points so as to present a more contracted figure; Fig. 4 is a section along the line 4—4 of Fig. 2; Fig. 5 is a section along the line 30 5—5 of Fig. 2, both Figs. 4 and 5 showing the holding device in a normal or locked position; Fig. 6 is a section similar to Fig. 5 but with the connecting strip drawn through the yielding clamping member in an unlocked position; and Fig. 7 is a modified 35 form of the holding device of my invention.

Referring now more particularly to the detail construction of my invention as embodied in a skirt frame—I have shown a 40 frame comprising four vertical sections 1, 2, 3 and 4, each section being laterally adjustable with relation to the other sections. This matter of adjustment is, of course, old and my invention is directed more particularly 45 to an improved holding device and I have applied such a holding device at each of the portions A, B, C and D. The parts to be joined are connected by means of a ribbon-like member 5 which is suitably fixed to one section, preferably by means of rivets 6, 50 said strip 5 then extending between relatively yielding members 7, 8 which are suitably secured to each other preferably by means of rivets 9. The connecting strip 5 55 has a plurality of locking elements in the

form of indentations 10 suitably disposed along the strip while the relatively yielding members 7 and 8 carry devices adapted to coöperate with the holding indentations 10 of strip 5. These coöoperating devices comprise preferably a rivet member 11 which also serves to hold parts of the frame, and an indentation 8' in the bridge members 8, said elements 11 and 8' acting upon the concave and convex sides respectively of locking elements 10.

In Fig. 6 I have shown the strip 8 in the act of being drawn through the yielding members, illustrating the manner in which the yielding members separate to allow adjusting movement thereof.

In Fig. 7 I have illustrated another form of my invention in which the connecting strip 5 is provided with rectangular or elongated indentations 10' and correspondingly 75 shaped holding devices are provided in the relatively movable members 7, 8. By the use of the rectangularly shaped elements a more rigid holding means is provided, and thus relative lateral movement of the connected parts is more nearly prevented. The rectangularly shaped indentations 10' in the strip 5' are so constructed that the projecting portion enters the rectangularly shaped indentation of the bridge element, and the 80 rectangularly shaped indentation in the vertical strip 7 of Fig. 7 is adapted to enter the indented side of the movable strip. Thus the connecting strip may be drawn through the opening made by the bridge and vertical strips under opposing tension thereof 85 and yieldingly held in any one of a plurality of positions.

In operating the clamping device of my invention to secure different adjustment of 95 the part or parts which it connects the strip 5 is simply forced through the relatively movable yielding members 7, 8 said members 7, 8 separating as in Fig. 6 so as to allow such movement of the strip 5 until the desired degree of adjustment is secured.

While I have embodied my invention in a skirt frame for model forms I contemplate applying it in other ways than that shown, the particular arrangement shown being 105 simply for the purpose of illustration.

It will also be apparent that many changes and modifications of the embodiments shown will readily suggest themselves and therefore I do not desire to be limited 110

to the exact structure as shown and described but aim to cover all that which comes within the spirit and scope of the appended claims.

5. What I claim as new and desire to secure by Letters Patent is:

1. An adjustable frictional clamping device comprising a pair of relatively yielding members suitably secured together so as to 10 form an opening between them, and a ribbon like connecting strip extending through said opening in contact with said members and having a plurality of holding elements whereby said strip may be drawn longitudinally through said opening in either direction while under holding tension of said members and yieldingly held by said elements in different adjustments without locking.
- 20 2. An adjustable connecting device comprising a mounting member, a yielding bridge member suitably secured to the mounting so as to form a variable opening between them, a ribbon like connecting strip 25 extending through said opening in contact with said members and adapted to be drawn therethrough in either direction while under holding tension of the members, and co-operating means on said strip and members 30 whereby said strip may be yieldingly held in any one of a plurality of connecting positions.
3. A device of the character described 35 comprising a pair of relatively adjustable devices, a connecting strip secured to one of said devices, a yielding bridge member se-

cured to the other device so as to form a variable opening through which said strip extends in holding contact therewith, said strip thus being adapted to be drawn in 40 either direction through the opening under holding tension of the bridge member and attached device, registering concave and convex elements carried by the bridge member and attached device, and co-operating 45 elements for said last elements disposed along the strip whereby said strip may be yieldingly held in different positions to hold the connected devices accordingly.

4. A device of the character described 50 comprising a pair of adjustable devices, a connecting strip secured to one of said devices, a yielding bridge member secured to the other device so as to form a variable opening, registering concave and convex elements positioned within said opening and carried by said bridge member and associated device, said strip extending through said opening and yieldingly held by said elements whereby said strip may be drawn 55 through the opening in either direction under holding tension of the elements, and indentations in said strip adapted to co-operate with said elements whereby said strip is 60 yieldingly held in adjusted positions.

Signed by me at Chicago, county of Cook, and State of Illinois, in the presence of two witnesses.

THOMAS S. LEVIS.
